UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A FRAME FOR TABLE-TOPS.

SPECIFICATION forming part of Design No. 23,520, dated July 31, 1894.

Application filed June 7, 1894. Serial No. 513,829. Term of patent 3½ years.

To all whom it may concern:

Be it known that I, LOTHAR VON GRAVE, a subject of the Emperor of Germany, residing at Wallingford, New Haven county, Connecticut, have invented and produced a new and original Design for Frames for Table-Tops, &c., of which the following is a specification, reference being had to the accompanying drawing, forming part of the same and where-
in the figure is a face view of a frame illustrating my design.

The essential characteristics of my design consist in an ornamental rim surrounded by a border of openwork formation, having heart-like representations interposed between scroll-like figures.

In the drawing *a* represents an ornamental rim which is surrounded by a border *A* of openwork formation having heart-like representations *b* interposed between scroll-like figures *c*. Portions of the openwork border *A* have chased surfaces as shown at *d*.

What I claim is—

The design for frames for table-tops, &c., substantially as shown and described.

LOTHAR VON GRAVE.
